UNITED STATES PATENT OFFICE.

TRUMAN S. FULLER AND NATHAN H. ADAMS, OF SCHENECTADY, NEW YORK, ASSIGNORS TO GENERAL ELECTRIC COMPANY, A CORPORATION OF NEW YORK.

THERMOELECTRIC GENERATOR.

Application filed March 31, 1925. Serial No. 19,685.

The present invention relates to improvements in thermo-electric generators of a type adapted for operating small electrical apparatus such as the space current devices used in radio broadcast reception.

It is an object of our invention to provide a thermopile unit with a convactor or radiator, so arranged and proportioned, that the proper difference in temperature may be maintained between the hot and cold junctions of the thermopile.

It is a further object of our invention to provide means for rigidly supporting a plurality of opposing thermopile units and their associated convectors in a definite position with respect to each other.

While various methods for cooling the cold junctions of thermopiles have been proposed they have generally been inefficient, cumbersome, and often impracticable. In the present device efficient cooling is maintained by an arrangement of thin metal plates in close thermal relation with that portion of the thermopile which includes the cold junctions. The cooling plates which comprise the convactor are in thermal contact with the thermopile from a point including the cold junction of the thermopile to a point less than midway between the hot and cold junctions. We have found that if the cooling plates are extended closer to the hot junctions the efficiency of the thermopile is lowered. The distance between adjacent convactor plates is widened at the outer portions thereof in order to provide sufficient area for air convection currents to pass between the plates. While the cooling means disclosed in the present case may be used with various types of thermopiles it is particularly adapted for use with a thermopile of the type disclosed in the co-pending application of Nathan H. Adams, Serial No. 19,733, filed March 31, 1925.

The novel features which we believe to be characteristic of our invention are set forth with particularity in the appended claims. Our invention itself, however, both as to its organization and method of operation will best be understood by reference to the following description taken in connection with the following drawing in which Fig. 1 is a plan view of the thermo-electric generator, a portion of the convactor or cooling means being broken away. Fig. 2 is a perspective view of the thermo-electric generator. Fig.

3 is a perspective view of the convactor associated with each thermopile. Fig. 4 is a cross-section taken on line 4-4 of Fig. 1. Fig. 5 is a cross-section taken on line 5-5 of Fig. 1. Fig. 6 is a perspective view of a portion of one of the thermopiles.

Referring to the drawing, we have indicated at 1 and 2 a pair of opposed thermopiles of the type disclosed in the above co-pending application of Nathan H. Adams. 65 Each thermopile has a main body portion 3, a grooved end or head portion 4 and a reduced connecting portion 5. The unlike metal plates forming the thermopile are separated by insulation as indicated at Fig. 6. 70 The thermopiles are arranged with their grooved portions in abutting relation to form a central cavity within which is located an electric heater 7. The heater is provided at the bottom end thereof with a pair 75 of terminals 8 which are adapted to cooperate with a socket member and connector 9, whereby the heater may be supplied with current. An alundum cylinder 10, provided with slots so that it may slide upon the reduced connecting portions 5 of the thermopile, substantially surrounds the head portions of the thermopiles and heater. Asbestos wool or the like 11 fills the space between the thermopile and the inner wall of cylinder 10. 80

A convactor or cooling means is associated with each thermopile. Each convactor comprises a plurality of thin metal plates 12 of aluminum or like material, each plate having a slot 13 of substantially the depth and width of the thermopile with which it is associated. Adjacent plates 12 are separated by U-shaped aluminum spacing means 14. The associated thermopile is inserted in the slot 90 formed in each convactor so that one end of the convactor is substantially flush with that end of the thermopile which includes the cold junctions.

Slotted I shaped end plates 15 and 16 are 100 connected to the outer and inner ends respectively of each convactor by means of bolts 17 and serve to support the convactor and its associated thermopile. The outer end plates 15 are each provided with a narrow vertical slot 18 which is enlarged near its upper and lower end to provide openings for conductors 19 to 22 inclusive which are connected to the outer members of the thermopiles. Thin insulating strips of mica or 110

similar material electrically insulate the thermopile for this convector and end plates.

In order to maintain the convector in good thermal contact with the sides of each thermopile the end plates are supplied with two pairs of metal blocks 23 attached to the end plates by means of screws 24. A screw 25 engages each pair of opposed blocks 23. By adjusting screw 25 the thermal contact of the convector and thermopile may be varied.

The inner end plates 16 are provided with a central slot of substantially the same depth and width as the associated thermopile. A plate 26 bears on the top of each thermopile. A plate 27 is provided at each end with grooves 28 and cooperates with each pair of end plates 15 and 16. The screw 29 engages in plate 27 and bears at its outer end against plate 26. By adjusting screw 29 the compression of the thermopile may be varied.

In order that the thermopiles may be assembled in a fixed position about the central heater each end plate is provided with openings through which bolts 30 extend. The ends of bolts are threaded and provided with nuts 31. By adjusting nuts 31 the heater may be firmly clamped between the opposing thermopiles 1 and 2 and the thermopiles themselves rigidly maintained in alignment.

Insulating blocks 22 are mounted at the upper end of each end plate 15. A conductor bar 33 is mounted on insulating blocks 32 and connected at each end to one of the terminals of a thermopile. The other terminals of each thermopile are connected to a socket member 34 mounted on an end plate 15 by one of the bolts 17. The connecting member 35 may extend through grooves in the bottom of the end plate members 15 and 16 if desired.

What we claim as new and desire to secure by Letters Patent of the United States, is:—

1. In combination a thermopile having a plurality of superposed unlike metal plates, and a plurality of integral, relatively thin, metal cooling plates in thermal contact with opposite edges of said unlike plates.

2. In combination a thermopile having a plurality of superposed unlike metal plates and a plurality of relatively thin metal cooling plates in thermal contact with opposite edges of said unlike plates, said unlike plates and cooling plates being in planes substantially perpendicular to each other.

3. In combination a thermopile having a plurality of superposed unlike metal plates, and a plurality of integral, relatively thin, metal cooling plates in thermal contact with opposite edges of said unlike plates and means for controlling the thermal contact between said integral plates and the opposite edges of said unlike plates.

4. In combination a convector comprising a plurality of relatively thin metal plates,

each plate having a slot adapted to accommodate a thermopile and the slots in the several plates being in alignment, a plurality of end plates, and means for supporting said convector between said end plates.

5. In combination a convector comprising a plurality of relatively thin metal plates, each plate having a slot and the slots in the several plates being in alignment, a thermopile within said slots, a plurality of end plates and means for supporting said convector between said end plates.

6. In combination a thermopile having a plurality of superposed unlike metal plates and a convector comprising a plurality of relatively thin, metal plates in thermal contact with opposite edges of said unlike plates, a plurality of end plates and means for supporting said convector between said end plates.

7. In combination a thermopile having a plurality of superposed unlike metal plates and a convector supporting said thermopile, said convector comprising a plurality of relatively thin, metal plates in thermal contact with opposite edges of said unlike plates, a plurality of end plates and means for supporting said convector between said end plates.

8. In combination a convector comprising a plurality of relatively thin metal plates, each plate having a slot and the slots in the several plates being in alignment, a thermopile positioned in said slots so that a portion of the thermopile which includes the cold junctions of said thermopile is in thermal contact with said convector, a plurality of slotted end plates, means for supporting said convector between said end plates, and means cooperating with said end plates for adjusting the thermal contact between said convector and thermopile.

9. In combination a convector comprising a plurality of relatively thin metal plates, each plate having a slot and the slots in the several plates being in alignment, a thermopile positioned in said slots so that a portion of the thermopile which includes the cold junctions of said thermopile is in thermal contact with said convector, a plurality of end plates, means for supporting said convector between said end plates and means cooperating with said end plates for compressing the elements of said thermopile.

10. In combination a plurality of thermopiles, each thermopile having a grooved head portion, said thermopiles being arranged in abutting relation to form a central cavity, an electric heater in said cavity, and means for clamping said heater between said thermopiles.

11. In combination a plurality of thermopiles, each thermopile having a grooved end portion, said thermopiles being arranged in alignment with the grooved portions in abut-

ting relation to form a central cavity, means for supplying heat to said cavity, a convector associated with each thermopile and supporting one end of the associated thermopile, a plurality of end plates, means for supporting said convectors on said end plates, and means associated with said end plates for maintaining said thermopiles in alignment.

12. In combination a thermopile comprising a plurality of unlike metal plates and a convector supporting said thermopile, said convector including a plurality of relatively thin metal plates in thermal contact with the opposite edges of said unlike plates, a plurality of end plates, means for supporting said convector on said end plates, and a socket member mounted on one of said end plates and adapted to be electrically connected to said thermopile.

13. In combination a plurality of thermopiles, each thermopile having a grooved end portion, said thermopiles being arranged in alignment with the grooved portions in abutting relation to form a central cavity, means for supplying heat to said cavity, a convector associated with each thermopile and supporting one end of the associated thermo-

pile, a plurality of end plates associated with each thermopile, means for supporting 30 said convectors on said end plates, an insulator mounted on one of the end plates associated with each thermopile, a conductor bar mounted on said insulators and a connection between said bar and each of said 35 thermopiles.

14. In combination a convector comprising a plurality of relatively thin metal plates, each plate having a slot, and the slots in the several plates being in alignment, 40 and a thermopile positioned in said slots so that a portion of the thermopile which includes the cold junction is in thermal contact with said convector.

15. In combination a thermopile having 45 a plurality of superposed unlike metal plates, and a convector cooperating with the cold junctions of said thermopile, and supporting said thermopile, said convector comprising a plurality of relatively thin metal 50 plates in thermal contact with opposite edges of said unlike plates.

In witness whereof, we have hereunto set our hands this 30th day of March 1925.

TRUMAN S. FULLER.
NATHAN H. ADAMS.
